(57) **CLAIM**

The ornamental design for a display screen portion with graphical user interface, as shown and described.

DESCRIPTION

FIG. 1 illustrates a front view of a display screen portion with graphical user interface depicting a first embodiment of the claimed design;

FIG. 2 illustrates a front view of a display screen portion with graphical user interface depicting a second embodiment of the claimed design;

FIG. 3 illustrates a front view of a display screen portion with graphical user interface depicting a third embodiment of the claimed design;

FIG. 4 illustrates a front view of a display screen portion with graphical user interface depicting a fourth embodiment of the claimed design;

FIG. 5 illustrates a front view of a display screen portion with graphical user interface depicting a fifth embodiment of the claimed design;

FIG. 6 illustrates a front view of a display screen portion with graphical user interface depicting a sixth embodiment of the claimed design;

FIG. 7 illustrates a front view of a display screen portion with graphical user interface depicting a seventh embodiment of the claimed design;

FIG. 8 illustrates a front view of a display screen portion with graphical user interface depicting an eighth embodiment of the claimed design;

FIG. 9 illustrates a front view of a display screen portion with graphical user interface depicting a ninth embodiment of the claimed design; and,

FIG. 10 illustrates a front view of a display screen portion with graphical user interface depicting a tenth embodiment of the claimed design.

The outermost broken-line rectangle illustrates a portion of a display screen and forms no part of the claimed design.

(Continued)

The remaining broken lines illustrate portions of the graphical user interface and form no part of the claimed design.
